EXHAUST UNIT

Paul F. Jettinghoff, Jackson, Mich., assignor to Walker Manufacturing Company, Racine, Wis., a corporation of Delaware

Filed June 12, 1963, Ser. No. 75,329

Term of patent 14 years

(Cl. D14—3)

I claim:

The ornamental design for an exhaust unit, substantially as shown.
